UNITED STATES PATENT OFFICE.

CHARLES LOOMIS GRIMES AND FRANK HARRINGTON WILLIAMS, OF MOLINE, ILLINOIS, ASSIGNORS TO WILLIAMS, WHITE & CO., OF SAME PLACE.

REAPING AND MOWING MACHINE.

SPECIFICATION forming part of Letters Patent No. 357,527, dated February 8, 1887.

Application filed June 18, 1886. Serial No. 205,574. (No model.)

To all whom it may concern:

Be it known that we, CHARLES LOOMIS GRIMES and FRANK HARRINGTON WILLIAMS, of Moline, in the county of Rock Island and State of Illinois, have invented certain new and useful Improvements in Reaping and Mowing Machines, of which the following is a specification.

Our invention relates to reaping and mowing machines; and the improvements consist in various features and details of construction hereinafter set forth.

The machine is of that general type in which the cutter or sickle and finger-bar are jointed to and carried by an L-shaped bar or frame at the angle of the latter, the two ends of the frame being jointed to the main frame of the machine in such manner as to permit the bar to rise and fall freely under manipulation of a suitable lever; and the improvements relate, mainly, to the construction of said L-shaped frame and the manner of attaching the cutter and adjusting devices thereto.

In the accompanying drawings, Figure 1 is a perspective view of the improved machine; Fig. 2, a top plan view of the same; Figs. 3 to 5, views illustrating various details hereinafter explained.

A indicates the main frame, formed or furnished with boxes to receive the revolving axle B, on which are mounted ground-wheels C C, the frame being also fashioned to receive the driving-gear, the tongue D, and seat spring or standard E, essentially as in other machines of this class. The wheels are loose upon the axle B, and furnished with pawls to engage with ratchets on the axle, to permit backing and turning, as usual.

The gearing consists of a main gear-wheel, F, keyed upon the axle B; a combined pinion and gear, F' F'', mounted upon a short shaft, G, having journals *a* eccentric to its axis and seated in suitable bearings in frame A; a combined pinion and bevel gear-wheel, F³ F⁴, loosely mounted upon the main axle B, and a bevel-pinion, F⁵, on a shaft, H, which pinion remains always in mesh with bevel-gear F⁴. Shaft G has one of its journals extended outward beyond the frame A and furnished with

a hand-lever, I, the body of which is preferably formed of a flat steel bar, said lever serving to turn the shaft G and throw its main body forward or backward, thereby causing pinion F' to mesh with or to become disengaged from gear F, as desired. The lateral swinging of bar I enables it to engage with or be disengaged from a locking lug or stud, J, which serves to retain the lever and shaft G and pinion F in operative position after adjustment. Shaft H is journaled in a long box or bearing on the main frame A, and carries at its forward end a wheel, K, provided with a wrist-pin, L, to which is connected the pitman through which motion is given to the cutter-bar or sickle, as usual.

As shown in Fig. 2, frame A has a forward extension, in which the bearing for shaft H is formed, and at the front of this extension there is formed a cavity or depression, A', to receive and protect the wheel K and wrist-pin L.

At the forward side of the enlargement or head in which the cavity A' is formed there is formed a socket, b, to receive the flattened end *c* of one arm of an L-shaped bar or frame, M, the other arm of which has a similarly-flattened end, *d*, which enters a socket, *d'*, formed at the under side of the main frame A near the wheel C, at the cutting side of the machine, the two flattened ends being secured in their sockets by and adapted to swing upon bolts *d*, passing through them and the walls of their sockets.

The bar M is of the form best shown in Fig. 3—that is to say, it is bent into substantially the shape of the letter L or V, with a short branch, *e*, connecting the two main arms or branches M' M''.

The portion *e* is “upset” by hammering or forging, to give greater strength and to produce bearing-faces *f* *f'* at right angles to the branch M', for a purpose presently explained, and this is an important feature of the present improvements. Encircling the branch M' of bar M is a sleeve, N, one end of which abuts equally against the face *f*. The sleeve N is formed with a head, *g*, perforated to receive a bolt or pin, *h*, which also passes through

the ears *i* of shoe *O*, and thus produces a flexible connection between the head and shoe, as usual.

Projecting from the upper side of sleeve *N* 5 is an arm, *N'*, through which passes one arm of a clamping-bolt, *P*, the other arm of which passes down in front of and bears against the face *f'* of the upset portion *e* of the bar *M*, thus serving to hold the end of sleeve *N* firmly 10 against the bearing-face *e*. Nuts *P'* and *P''* permit the clamping-bolt to be adjusted from time to time to compensate for wear of the parts and to keep them always tight and free from play.

15 When it is desired for any cause to remove sleeve *N*, it is only necessary to loosen one of the nuts, swing the clamping-bolt upward, and slide the sleeve along branch *M*. The arm *N'* of sleeve *N* is extended upward beyond the point where the clamping-bolt *P* passes through it, and it is perforated to receive the laterally-bent forward end of a rod, *Q*, the rear end of which is joined to a handlever, *R*, which lever is pivoted to the main frame *A*, and provided with a locking dog or pawl, *j*, to engage with a sector-rack, *S*, by which means the lever may be retained at any desired adjustment.

20 As shown in Fig. 2, branch *M'* of bar *M* and the sleeve *N* encircling the same are in a plane parallel with the cutting mechanism. When, therefore, the lever *R* is thrown forward and caused to rock the sleeve *N* forward at its upper side, it causes the front end of shoe *O* to be depressed and the rear end to be raised, and as the finger-bar is rigidly secured to the shoe it, together with the cutter-bar or sickle, 25 partakes of the same motion, thus enabling the cutting mechanism to cut close to the ground or to follow close to the bottom of a depression. If the lever be thrown backward the reverse action follows, the front of the shoe and finger-bar being raised, so that they may freely pass over slight obstructions, follow the inclination of a gully or depression 30 in passing out of the same, or cut higher from the ground, as required.

35 The shoe *O* is formed with a lateral tail or arm, *O'*, in rear of sleeve *N* and extending to one side of head *g* and bolt *h*, upon which arm bears one end of a gag-lever, *T*, pivoted between ears or lugs *N''*, formed upon the under side of sleeve *N*. The rear end of the gag-lever is connected by a chain or band, *U*, with a lifting-lever, *V*, pivoted upon the tongue *D*.

40 The tail or arm *O'* of the shoe being extended inward or backward beyond the hinge pin or bolt *h*, it follows that if downward pressure be applied to said arm *O'* the sleeve *O* will be caused to tip or swing upon the bolt *h*, thereby lifting up the outer or free end of the finger-bar and sickle, and enabling them so clear very considerable obstructions, or to swing up to a position which will enable the machine to pass through gateways, &c.

45 The movement of the gag-lever is limited by the wall or face of the space between the

50 lugs or ears *N''*, between which lugs said lever is pivoted. From this it follows that if the gag-lever be moved by lifting-lever *V* until it reaches its limit or stop, and the movement of the lifting-lever be continued, the entire frame or bar *M* and the parts carried thereby will be bodily lifted from the ground and thus 55 enabled to clear obstructions close to as well as more distant from the wheeled frame.

55 The lifting-lever *V* is furnished with a dog or pawl, *l*, to engage with a sector-plate or rack, *W*, as indicated, by which means the parts may be retained in an elevated position. 60 As the gag-lever acts upon and depresses the tail or arm *O'* of shoe *O*, the bearing-point constantly changes, and in order to maintain a due leverage and proper bearing to prevent the shoe with its finger-bar and sickle from 65 getting out of the control of the gag-lever the end of said lever is made in the form illustrated in Fig. 4—that is to say, it resembles a hook, the curved bearing-face *k* of which is eccentric to the pivot on which the gag-lever turns or rocks. When the parts are in their normal position, as in Fig. 4, the lever will bear upon the tail or arm *O* near the inner point or nose of the hook-shaped end; but as the two parts swing downward the bearing-point will constantly shift along the curved face *k*, but will remain practically unchanged upon the tail or arm *O*, thus causing the gag-lever to maintain a perfect and uniform control over the shoe and cutting mechanism.

70 *X* indicates the draft-rod, which, as usual, runs from the thrust-bar (which in this case is branch *M'* of bar *M*) to and through a guide, *Y*, on the under side of the tongue *D*.

75 For the purpose of affording a firm and convenient attachment for the draft-rod the branch *M''* of bar *M* is "upset" or enlarged at a suitable point to form a boss, *Z*, which is perforated to form an eye, into which to hook and fasten the rear end of the draft-bar, as 80 shown in Figs. 1 and 2.

85 We are aware that it is not new to employ an *L*-shaped or *V*-shaped bar to carry the cutting mechanism, that an eccentric shaft has been employed to carry a part of the gearing 90 of a mowing-machine to enable it to be thrown into and out of mesh with other parts thereof, and that various other parts of the machine are of essentially usual construction.

95 Having thus described our invention, what we claim is—

1. In a reaping or mowing machine, a cutter-supporting frame, *M*, consisting of two main branches connected by an upset or enlarged portion, *e*, substantially as shown and 105 described.

2. The herein-described cutter-supporting frame *M*, having branches *M' M''*, upset portion *e*, and perforated boss *Z*.

3. In a mowing or reaping machine, the 110 combination of a main frame, a cutter-carrying frame, *M*, hinged thereto and consisting of branches *M' M''* and connecting portion *e*, sleeve *N*, provided with arm *N'*, and clamp-

ing-bolt P, passing through said arm and extending outward and downward over face f' of the connecting portion e of frame M.

4. In a reaper or mower, the combination, 5 with bar or frame M, having branches M' M² and connecting portion e, sleeve N, encircling branch M', provided with arm N' and abutting against the inner face of portion e, bent clamping-bolt P, passing through said arm and 10 bearing against the outer face of portion e, and nuts P' P², applied to bolt P and serving to adjust the same, as required.

5. In a reaper or mower, the combination 15 of a main frame, a cutter-supporting frame hinged thereto, a sleeve encircling and rotatable upon a branch of said supporting frame, and provided with a head or boss, a shoe or cutting mechanism hinged to said head or boss, the shoe being formed with a lateral tail or 20 arm, and a gag-lever pivoted to the sleeve and bearing at one end upon the lateral tail or arm of the shoe.

6. In a mower, the combination, with a main frame and a cutter-supporting frame hinged thereto, of a rocking sleeve, N, mounted upon 25 a branch of the cutter-supporting frame, a shoe, O, pivoted to sleeve N and provided with tail or arm O', gag-lever T, also pivoted to sleeve N, and having its bearing end or face curved, substantially as shown and described. 30

7. In combination with main frame A and hinged frame M, loose sleeve N, provided with arm N', lugs or ears N², and head g, shoe O, hinged to head g and provided with tail or arm O', and gag-lever T, pivoted to ears N², 35 all substantially as described and shown.
